UNITED STATES PATENT OFFICE.

HARRY S. FOLGER AND TOREY ROSS, OF CHICAGO, ILLINOIS; SAID ROSS ASSIGNOR TO
SAID FOLGER.

HOLDER FOR PADS, STAMPS, AND PENS.

1,300,153.

Specification of Letters Patent.

Patented Apr. 8, 1919.

Application filed August 3, 1918. Serial No. 248,100.

To all whom it may concern:

Be it known that we, HARRY S. FOLGER and TOREY Ross, citizens of the United States of America, and residents of Chicago, county of Cook, and State of Illinois, have invented certain new and useful Improvements in Holders for Pads, Stamps, and Pens, of which the following is a specification.

Our invention relates to a holder which will contain an ink pad, will be connectible to the end of a pen, will provide a chamber for receiving a stamp connected to the pen, and will be of such proportions that the entire combination of parts may be carried in the pocket as an ordinary fountain pen is now carried. In banks, railway offices and commercial houses of various kinds there are officials who are required to be continually signing documents and who accompany their signatures with a rubber stamp impression of some character. Such officials frequently have to move about from place to place and have to sign papers at other places than at their desks. To meet the requirements of such officials we have devised a stamp holder which is attached to a fountain pen. Such holder for such pen is the subject matter of our pending application Serial Number 225,518, filed March 29, 1918. The object of the present invention is to make a pad and holder for such pen and stamp, and to make such holder in such form that it may be readily carried in the pocket.

In the accompanying drawings

Figure 1 is an elevation of the entire device, the pad box or holder being shown closed;

Fig. 2 is a similar view with the box open;

Fig. 3 is a sectional elevation on line 3—3 of Fig. 1;

Fig. 4 is a transverse section on line 4—4 of Fig. 1; and

Fig. 5 is an end elevation of the box with the pen and stamp removed.

The fountain pen 10 is of the ordinary kind. To this is attached an adjustable sleeve 11 which has on its end a laterally projecting holder 12 for the rubber type 13. These parts are so constructed and related to each other that by holding the penholder at slightly different angles the owner of the device may use it either for writing or for stamping on a document presented.

The ink pad 14 is held in a box 15 which has at one end a chamber 16 for receiving the stamp holder 12. A cover 17 is connected by a hinge 18 to the box 15 at the end opposite the chamber 16. When the box is closed there is a circular opening 19 (Fig. 5) through which the penholder 10 projects. This circular opening is made by joining two semi-circular cuts, one of which is in the box and the other of which is in the cover. The partition 20 between the chamber 16 and the pad-holding chamber also has in it a similar semi-circular cut in which the inner end of the penholder rests when the box is closed. These cuts fitting on the penholder at two points hold the box and pen in line so that no strain will be brought upon the stamp holder 12 by reason of the pen and box being pushed out of line.

On the cover are small inward projections 21 which engage corresponding depressions 22 (Fig. 2) in the exterior of the box. These are of an ordinary character and need no special description. Their function is to normally hold the box in a closed condition.

The spring prong 23 secured on the outside of the cover 17 is the same as that ordinarily used with pens and pencils and needs no description.

A fountain pen with the attachment 11—12—13 is a convenience because it furnishes pen and rubber stamp in one instrument. The holder herein described is a convenience in connection with this pen and stamp in that it holds a pad to be used with the stamp and has chambers which inclose and protect both the pen point and the stamp from injury and also from soiling the clothes. The chamber for the pen point is that space between the pad 14 and the cover 17.

What we claim is:

1. A box and a pad therein, said box having a chamber adjacent to and separated from the pad, and a cover hinged to said box, said box and cover when closed being arranged to engage a penholder and protect a stamp secured to such holder.

2. In a device arranged to be used in connection with a pen and a rubber stamp secured thereto, a box having two chambers therein, an ink pad in one chamber, the other chamber being an open space for the reception of the stamp attached to the pen, and a cover hinged to the box, said cover being ar-

ranged to engage the holder of the pen and hold the pen and stamp in a definite relationship to the box.

3. The combination with a rubber stamp having a handle secured thereto, of a box arranged to be opened and closed and having a chamber arranged to receive the rubber stamp, an ink pad within the box ad-

jacent to the space occupied by the stamp, and means associated with the box for engaging said handle so as to hold the box and stamp in a definite relationship to each other. 10

HARRY S. FOLGER.
TOREY ROSS.
